ADJUSTABLE WEIGHT BALL FOR BOWLING
Albert A. Roike, 2764 Creston Ave., Bronx, N.Y.
Filed Oct. 31, 1962, Ser. No. 234,453
2 Claims. (Cl. 273—63)

This invention relates to a ball construction especially intended for use in bowling, but also useful in other games and sports and in allied fields. The invention is particularly directed at a ball having two separable hollow parts in which are removably disposed nested, abutted, balanced hemispherical weights.

According to the invention the weights can be selectively removed for varying the weight and mass of the ball. The outer parts of the ball are held together by detachably engaged threaded rods or a nut and bolt which pass axially through the weights in the ball. Special tools are provided for detaching the rods and for removing selected weights from the separated parts of the ball.

It is therefore a principal object of the invention to provide a ball useful in bowling or the like, having separable hemispherical parts in which are removable balanced weights.

A further object is to provide a novel hemispherical weight for a bowling ball.

Another object is to provide bowling ball weights with novel means for removing the same from separated parts of the ball.

Still another object is to provide a bowling ball with means for selectively varying its weight and mass according to the requirements of a particular player or particular game.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

FIG. 1 is a side elevational view of a bowling ball embodying the invention.

FIG. 2 is another side elevational view of the ball rotated 90° from FIG. 1, and taken on line 2—2 of FIG. 1.

FIG. 3 is a cross-sectional view taken on line 3—3 of FIG. 1.

FIG. 4 is a cross-sectional view taken on line 4—4 of FIG. 3, one inner hemispherical weight being removed.

FIG. 5 is an exploded perspective view of parts of the bowling ball embodying the invention.

FIG. 6 is a perspective view of a fastening tool.

FIG. 7 is a perspective view of a weight removing tool.

Referring to the drawings, there is shown in FIGS. 1 and 2 a spherical ball 10 having two separable hemispherical parts 12^a and 12^b. Part 12^a as shown in FIGS. 1—5 is a hollow hemispherical shell having an outer convex side 14, an inner concave side 16 and a flat annular diametral face 20. A cylindrical sleeve or ridge 23 extends axially outward from face 20. Ridge 23 has a flat outer annular face 18 and a cylindrical inner wall 22. Face 18 is disposed in a plane spaced from and parallel to the plane of face 20. Wall 22 may be slightly tapered outwardly from the face 20 to face 18. A metal tube 24 with lateral solid lugs 25 is cast in the body of part 12^a, projecting inwardly therefrom. A recess 26 is formed in the body outwardly of and in alignment with the tube. A group of holes 32 extend substantially radially inward of the part 12^a from outer side 14 toward inner side 16. These holes serve as finger gripping means when the ball is in use.

2

Part 12^b as shown in FIGS. 2—5 is also a hollow hemispherical shell with outer convex side 34, inner concave side 36, and a flat annular diametral face 42 extending radially outward from side 36. An annular recess 40 has a cylindrical wall 44 and a radial face 38 concentric therewith. Ridge 23 fits snugly around wall 44 so that the flat annular face 18 of the ridge 23 abuts wall 38 of the recess 40, and the cylindrical outer wall 44 abuts inner wall 22. The wall 44 may be tapered radially inwardly slightly to effect a smooth readily detachable joint with wall 22 which may also be tapered as mentioned above.

An internally threaded tubular member 46 with one end closed is cast into the shell of part 12^b and is provided with lateral solid lugs 48 to keep it from turning. Tube 24 and tubular member 46 are in alignment.

A hemispherical hollow weight 60^a seats snugly in the ball part 12^a. Weight 60^a has a convex outer side 62^a, a concave inner side 64^a, and a flat annular diametral face 66^a. Side 62^a abuts inner side 16 of part 12^a while face 66^a is disposed coplanar with face 20. Weight 60^a has an axial hole 68^a registering with recess 26 so that the tube 24 passes therethrough. Four circumferentially spaced recesses or holes 70 are formed inside of the weight 60^a. These holes extend radially outward of inner side 64^a and are spaced slightly from face 66^a. Holes 70 are provided for engagement by a tool 75 shown in FIG. 7 and used to remove weights from the ball parts 12^a, 12^b.

A hemispherical hollow weight 72^a seats snugly in the weight 60^a. Weight 72^a has a convex outer side 74^a which abuts inner side 64^a of weight 60^a, and a concave inner side 76^a. The weight has a flat annular face 78^a which is coplanar with face 66^a, and a central axial hole 80^a registering with hole 68^a to receive tube 24. Four circumferentially spaced recesses or holes 70^a are formed inside of weight 72^a and like holes 70 are provided for engagement by tool 75 to remove the weight from inside of weight 60^a.

A hemispherical solid weight 82 seats snugly in weight 72^a. Weight 82 has a convex outer side 84^a which abuts inner side 76^a of weight 72^a and a flat, circular, diametral face 86^a which abuts a similar face 86^b of a similar hemispherical solid weight 82^b. Weight 82 has a central bore 88^a which receives the tube 24. The bore registers with hole 80^a in weight 72^a. Four radial, spaced holes 90^a are formed at the inner end of hole 88^a near face 86^a for engagement by tool 75 to remove the weight from the interior of weight 72^a.

A hemispherical weight 60^b similar to weight 60^a in construction fits snugly inside part 12^b and the outer convex side 62^b abuts concave inner side 36 of part 12^b. The flat annular face 66^b of weight 60^b abuts face 66^a of weight 60^a. Hole 68^b in weight 60^b is aligned with hole 68^a in weight 60^a and receives the tube 24. The hole 68^b registers with tube 46 in part 12^b. Spaced holes 70^a are provided in the inner side of weight 60^b arranged like holes 70 in weight 60^a.

A hemispherical hollow weight 72^b seats snugly in weight 60^b. Its outer convex side 74^b abuts inner concave side 64^b of weight 60^b. The flat annular face 78^b of weight 72^b abuts flat face 78^a of weight 72^a. Central axial hole 80^b is aligned with hole 80^a and registers with hole 68^b to receive tube 24. Spaced holes 74^b are arranged like holes 70^a to engage tool 75, for removal of the weight from weight 60^b.

The hemispherical solid weight 82^b has a central axial bore 88^b which registers with bore 88^a in weight 82^a. Circumferentially spaced radial holes 84^a are provided in weight 82^b near the flat face 86^b, for engagement by tool 75.

The hemispherical weights 60^a, 72^a and 82^b nest one within the other and all are contained inside ball part

12^a. Weights 60^b, 72^b and 82^b nest within each other and all are contained in ball part 12^b. The weights are arranged in pairs. Weights 60^a and 60^b are identical in structure, size and weight. Weights 72^a, 72^b are identical in structure, size and weight and weights 82, 82^b are identical in structure, size and weight. If desired, all weights may be the same and may be made of the same or different metal, plastic or other suitable materials. In any case the weights in each pair should be the same and may be interchanged with each other in the several ball parts 12^a, 12^b.

An elongated round externally screw threaded rod 59 is threaded through the aligned tube 24 and tubular member 46 so as to removably connect the ball parts 12^a and 12^b. The rod has a noncircular reduced head 52.

A spanner wrench 100 shown in FIG. 6 is provided for securing the ball parts together. This wrench has a shaft 102 with a noncircular socket opening 104 to fit over reduced noncircular head 52 of connecting rod 59. The wrench has a handle 106 extending perpendicular to the shaft at the other end thereof to facilitate turning the wrench. When the wrench is engaged with the head of rod 59 and is turned, the rod will turn to connect or disconnect the ball parts.

In FIG. 7 is shown tool 75. This tool has a generally V-shaped body formed from a strip of spring steel, springy plastic or other material. The tool has two flat legs 110, 111 flaring outwardly from the apex 112 of the tool. At the free ends of the legs are two prongs 114 which respectively engage in diametrically opposed holes 70, 70^a, 70', 74^b, 90^a, 84^a in any of the hemispherical weights. The legs are biased outwardly due to the springiness of the tool body and are normally spaced apart a distance greater than the spacing of the most widely spaced holes 70, 70^a. To engage in holes 70', 74^b the legs must be pressed manually inward toward each other. To engage in opposing holes 90^a or 84^a the legs must be compressed even further. When the legs are released, the spring tension at apex 112 will force the prongs into the opposing holes in the hemispherical weight to be removed from the ball or inserted therein. A supplementary, arcuate, leaf spring 115 is secured to intermediate points of legs 110, 111 by rivets 116 and increases the outward spring bias of the legs 110.

To adjust the weight of the ball, two, four or six weights will be removed or inserted from the ball parts. The weights must be removed in pairs to keep the remaining parts of the ball assembly in balance. If it is found desirable to balance the weight of the assembled ball parts with respect to the diameters taken through each of the finger holes 32 in ball part 12^a, then another group of similar finger holes 32' may be provided in ball part 12^b located between member 46 and recess 40. Each one of holes 32' will be diametrically aligned with a corresponding one of holes 32, when the ball parts are interfitted and secured together.

In order to insure proper alignment of the finger holes in the two ball parts, index marks M, M' may be provided on the outer sides of the respective ball parts. When these marks line up as indicated in FIG. 2, then the holes 32 are correctly aligned with holes 32'.

The invention has been described with particular reference to a bowling ball, but it will be apparent that it is applicable to any ball structure where a balanced ball of adjustable weight and mass is required. While the invention is particularly applicable to balls used in playing various games, it is also applicable to balls used in weight lifting, shot putting, and the like. It is also applicable to

balls used in other applications than sports and games. The weights, can, of course, have any desired magnitudes. In one practical embodiment a bowling ball was constructed with an outside diameter of about eight and one-half inches. The individual weights were about one pound each. The ball can, of course, be made in other sizes.

While I have illustrated and described the preferred embodiment of my invention, it is to be understood that I do not limit myself to the precise construction herein disclosed and that various changes and modifications may be made within the scope of the invention as defined in the appended claims.

Having thus described my invention, what I claim as new, and desire to secure by United States Letters Patent is:

1. A bowling ball construction of the character described comprising a pair of similar hemispherical body parts each of which is provided with a concentric hemispherical cavity, interlocking means between the opposed faces of said parts, one of said parts having an axial bore extending through the wall thereof, a tube secured in said bore with the inner end thereof extending in the cavity in the said one of said parts, the other of said parts having an internally threaded tube secured therein in axial alignment with said tube with the inner end thereof extending into the cavity in the said other of said parts; a first pair of similar hemispherical weights each of which is provided with a concentric hemispherical cavity, one of said weights being nested in each of said body parts with the outer surfaces thereof abutting the inner surfaces of said body parts; a second pair of similar hemispherical weights each of which is provided with a concentric hemispherical cavity, one of said second pair of weights being nested in each of said first pair of weights with the outer surfaces thereof abutting the inner surfaces of said first pair of weights; a pair of similar hemispherical flat-faced solid weights, one of said solid weights being nested in each of said second pair of weights with the outer surfaces thereof abutting the inner surfaces of said second pair of weights; said weights having axially aligned bores therein into which the inner ends of said tubes extend, and an externally screw-threaded rod disposed in said aligned tubes for removably holding said body parts together, said rod being provided with a reduced noncircular end for the reception of a turning tool, and said weights being selectively removable for adjusting the weight of said ball.
2. A bowling ball construction as defined by claim 1 in which said weights are provided with radial holes which are adapted to receive a tool for removal thereof.
